UNITED STATES PATENT OFFICE

TOM HAWKINS, OF VINITA, OKLAHOMA

FRUIT PRESS

Application filed June 20, 1932. Serial No. 618,312.

The invention relates to a fruit press and more particularly to a hydraulic cider press.

The primary object of the invention is the provision of a press of this character, wherein in the juices from fruits, for example, apples, can be conveniently extracted and the extracting operation is hydraulically controlled, the press in its entirety being of novel construction and is readily portable so that such press 10 may be used in stores or other places for the dispensing of the juices of the fruits on extraction thereof.

Another object of the invention is the provision of a press of this character, wherein 15 a hopper is arranged with crushing rolls, these being driven so that fruits introduced into the hopper will be crushed for their delivery in a crushed condition into an extractor barrel or cylinder, the latter being movable from receiving position to a position to be operated upon by a hydraulic press mechanism, the latter being of novel form.

A further object of the invention is the provision of a press of this character, wherein 25 in the same may be manually operated or automatically controlled and in the operation the juices from fruits will be expeditiously extracted therefrom and the same delivered for the merchandising of the same; the extractor barrel or cylinder being manually shiftable from receiving to extracting positions and such movement controls the working of the crusher rolls and the hydraulic device of the press.

A still further object of the invention is the provision of a press of this character, which is comparatively simple in construction, thoroughly reliable and efficient in its operation, readily and easily operated, strong, 40 durable, and inexpensive to manufacture.

With these and other objects in view, the invention consists in the features of construction, combination and arrangement of parts 45 as will be hereinafter more fully described in detail, illustrated in the accompanying drawings, which disclose the preferred embodiment of the invention, and pointed out in the claims hereunto appended.

50 In the accompanying drawings:—

Figure 1 is a side elevation of the press constructed in accordance with the invention.

Figure 2 is an end elevation thereof looking toward the delivery end of the press.

Figure 3 is a top plan view.

Figure 4 is a plan view of the extractor barrel or cylinder.

Figure 5 is a sectional view on the line 5—5 of Figure 4 looking in the direction of the arrows.

Figure 6 is a fragmentary view similar to Figure 1 looking toward the opposite side of the hydraulic control mechanism.

Figure 7 is a sectional view on the line 7—7 of Figure 6.

Figure 8 is a fragmentary vertical longitudinal sectional view through the press.

Similar reference characters indicate corresponding parts throughout the several views in the drawings.

Referring to the drawings in detail, the press comprises a frame A constituting a stand including corner uprights or legs 10 and 11 respectively, longitudinal top and bottom side sills 12 and 13 respectively, these being joined with the legs or uprights 10 and 11 in any desirable manner to effect rigidity. Mounted above the bottom side sills 13 in the stand constituted by the frame A is a juice delivery tray 14 having a discharge spout 15 at one end.

Built above the frame A and supported thereby is a hopper 16 having a downwardly tapered open discharge bottom 17, while arranged interiorly of the hopper 16 and journaled in the side walls thereof are the axles 18 of crusher rolls 19, these being arranged opposite each other and in close relation to one another so that fruits introduced into the hopper 16 through the open top thereof will be caused to pass between the rolls 19 and become crushed thereby for the discharge of the crushed material through the bottom 17 of said hopper. The rolls 19 are rotated reversely through the medium of a train of gears 20, one of which is made fast to a driven shaft 21 mounted in a bearing 22. This shaft has splined or keyed thereon the shiftable member 23 of a clutch, its companion member 24 being

made a part of a driven gear 25 which is loose upon the shaft 21 and meshes with a driving gear 26 fixed to a stud shaft 27 journaled in a bearing 28, the bearings 22 and 28 being made fast to the frame constituting the stand A. The gear 26 is united with a hand turning wheel 29 although in lieu of this wheel a belt wheel may be employed or a suitable connection had with a power source.

The tray 14 has its sides formed to provide tracks 30 and upon these tracks is adapted to be slidably mounted an extractor barrel or cylinder 31, the side wall and bottom being slotted as at 32 and 33 respectively so as to permit the discharge of extracted juices therethrough into the tray 14 in the operation of the press.

Mounted upon the frame A forwardly of the hopper 16 is a hydraulically controlled mechanism which comprises a plunger cylinder 34, the same being vertically disposed upon brackets 35 mounted upon the stand and working within this cylinder is the plunger 36 having the presser or piston head 37 which is adapted to be lowered from normally elevated position into the barrel or cylinder 31 for action upon its contents for the extraction of the juices therefrom. Next to the cylinder 34 is a fluid tank or cylinder 38 having a removable cover or head 39 so that liquid may be introduced thereinto, while at one side of the cylinder 34 is a pump 40, the latter having communication with the lower portion of the tank or cylinder 38 through the lead pipe 41 and its rotatable operating shaft 32 has splined or keyed thereto the shiftable member 43 of a clutch, the companion member 44 of which is formed with a gear 45 loose upon said shaft 42 and meshing with the driving gear 26. The pump 40 also has communication with the upper end of the plunger cylinder 34 by a lead pipe 46 so that on the operation of the pump the liquid within the tank or cylinder 38 will be forced under pressure by the pump 40 through the lead pipe 46 into the cylinder 34 for the operation of the plunger to lower the head 37 thereof into the barrel or cylinder 31 when the latter has been located below such head on the shifting of the barrel or cylinder in the tray 14 as will be obvious.

The cylinder 34 has at its upper end a return lead 47 therefrom into the tank or cylinder 38 and this lead is fitted with a rotatable cut-off valve 48 having a crank 49 for the turning thereof to open or close the same. This crank 49 has pivoted thereto an actuator rod 50 which is vertically disposed and slidably mounted externally upon the cylinder 34 while upon the plunger 36 is a trip 51 for actuating the actuator rod 50 when the plunger has reached the limit of its downward stroke. The valve 48 which is

normally closed, that is, when the plunger is at its full uppermost stroke, will be automatically opened to permit the liquid to be returned from the cylinder 34 into the tank or cylinder 38. The trip 51 is in the form of a stem and is made fast in the head 37. The actuator rod 50 has its lower end outturned and through which plays the stem 51, the latter being fitted with adjustable nuts disposed at opposite sides of the outturned end as is clearly shown in Figure 6 of the drawings. The plunger carries a crosshead 52 with which are connected coiled retractile springs 53, these being also connected to a crosshead 54 mounted at the top of the cylinder 34 and these springs 53 function to return the plunger to normal elevated position and in this upward movement of the plunger in the cylinder 34 the liquid forced thereinto by the pump 40 will be driven therefrom through the return lead 47 into the cylinder or tank 38, the lead 46 from the pump 40 being fitted with a suitable liquid check device 55 to prevent the return of the liquid therethrough as delivered into the cylinder 34 from the tank or cylinder 38 by the pump 40, the return of the liquid to the tank or cylinder 38 being had through the return lead 47 and such return being effected on the elevating of the plunger in said cylinder 34 as will be obvious.

The extractor barrel or cylinder 31 has exteriorly thereof a double acting cam 56 while suitably mounted at 57 upon the frame A are clutch shift levers 58 and 59 respectively, these being associated with the shiftable members 23 and 43 of the clutches controlling the operation of the shafts 21 and 42 respectively. The shift levers 58 and 59 are actuated by the double acting cam 56 on the barrel or cylinder 31 so that when the latter is moved beneath the hopper 16 the crusher rolls 19 will be actuated by the driving gear 26 for the crushing of the fruit or fruits introduced into the hopper 16 before delivery into the barrel or cylinder 31. Then when the said barrel or cylinder 31 is shifted beneath the plunger of the hydraulic mechanism the pump 40 will be operated from the drive gear 26, the clutches being thrown in or closed by the double acting cam 56 operating the clutch shift levers 58 and 59 as will be apparent. When the cam 56 rides off of either lever 58 or 59 the clutch will be thrown out automatically.

Journalized transversely in the frame A intermediate thereof is a rocking shaft 60 carrying at opposite sides of the stand the arms 61 which have connection through the medium of the pins 62 working in the slots 63 in the respective arms 61 with the extractor barrel or cylinder 31. One of the arms 61 is extended to provide a hand hold 64 for manual shifting of the barrel or cylinder 31 in the working of the press.

It will be apparent that in the working of the press the fruit to have the juices thereof extracted will be introduced into the hopper 16 and the extractor barrel or cylinder 31 will be positioned immediately beneath the bottom of such hopper to receive the crushed fruit when operated upon by the crusher rolls 19, these being driven from the driving gear 26. When the desired quantity of crushed material has been delivered to the extractor barrel or cylinder 31 the hand hold 64 is operated to shift the said barrel or cylinder 31 beneath the plunger of the hydraulically controlled mechanism and the pump 40 will be automatically driven from the gear 26 so that liquid from the tank or cylinder 38 will be forced into the cylinder 34 causing the plunger to be lowered into the barrel or cylinder 31 and thereby extracting the juices from the crushed material, the extracted juices being emitted or discharged through the slots 32 and 33 in the barrel or cylinder 31 into the tray 14 whence the same will be delivered from the spout 15 for the merchandising thereof.

It is of course understood that when the plunger is lowered the valve 48 is closed in the return lead 47 and immediately upon the throwing out of the clutch by disengaging its member 43 from the member 44 the springs 53 will become active for the automatic elevating of the plunger and simultaneously the valve 48 will be opened so that the liquid within the cylinder 34 will pass therefrom back into the tank or cylinder 38. Each clutch member 23 and 43 is held open or out of engagement with its companion member 24 or 44 by a spring 65. The pump 40 is mounted upon a bracket 66 carried by the frame A constituting the stand of the press.

From the foregoing it is thought that the construction and manner of operation of the press will be clearly understood and therefore a more extended explanation has been omitted.

What is claimed is:—

1. A press of the character described comprising a stand having a hopper, a juice tray in said stand below the hopper, hydraulically controlled extractor mechanism supported by the stand, crusher mechanism within the hopper, and independent control means for each of the mechanisms and located for engagement by a receiver when shifted upon the tray alternately beneath the hopper and extractor mechanism.

2. A press of the character described comprising a stand, a hopper in said stand, a juice tray in said stand below the hopper, an extractor barrel slidably beneath said hopper and supported within the tray, hydraulically controlled extractor mechanism supported by the stand and beneath which is to be moved said extractor barrel, crusher mechanism within the hopper, and independent control

means for each of the mechanisms and so located as to be engageable by the barrel during the movement of the barrel from one position to another.

3. In a press of the character described, a stand, a hopper on said stand, a plunger cylinder on said stand, a plunger operating in said cylinder, crusher rolls within said hopper, a fluid pump communicating with said cylinder and operative to effect the lowering of the plunger, an extractor barrel below the hopper and movable beneath said hopper and said plunger, and independent control means for the crusher rolls and plunger and so located as to be engaged by the barrel during its movement beneath the hopper and plunger.

4. In a press of the character described, a stand, a hopper on said stand, a plunger cylinder on said stand, a plunger operating in said cylinder, crusher rolls within said hopper, a fluid pump communicating with said cylinder and operative to effect the lowering of the plunger, an extractor barrel below the hopper and movable beneath said hopper and said plunger, independent control means for the crusher rolls and plunger and so located as to be engaged by the barrel during its movement beneath the hopper and plunger, and a juice tray arranged in said stand and movably supporting said extractor barrel.

In testimony whereof I affix my signature.

TOM HAWKINS.
